UNITED STATES PATENT OFFICE

164,630

COMBINED SUGAR AND CONDIMENT HOLDER

Samuel W. Friedman, Los Angeles, Calif.

Application May 6, 1950, Serial No. 9,758

Term of patent 3½ years

(Cl. D44—22)

To all whom it may concern:

Be it known that I, Samuel W. Friedman, a citizen of the United States, residing in Los Angeles, in the county of Los Angeles, and State of California, have invented a new, original, and ornamental Design for a Combined Sugar and Condiment Holder, of which the following is a specification, reference being had to the accompanying drawing, forming part thereof:

Fig. 1 is a top plan view of a combined sugar and condiment holder, showing my new design.

Fig. 2 is a side elevational view thereof.

Fig. 3 is a bottom plan view.

The dominant features of the design reside in the portions shown in full lines.

I claim:

The ornamental design for a combined sugar and condiment holder, substantially as shown and described.

SAMUEL W. FRIEDMAN.
